Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing our new design;

FIG. 2 is a bottom view thereof; and,

FIG. 3 is a rear perspective view thereof.

The contrast in shading represents a contrast in appearance only and does not represent any particular color, material, texture or finish. The broken lines depicting the remainder of the shoe show features that form no part of the claimed design.
